UNITED STATES PATENT OFFICE.

MATTHEW H. LOUGHRIFFE, OF BOGOTA, NEW JERSEY.

RAILWAY-TRAFFIC-CONTROLLING SYSTEM AND APPARATUS.

1,242,456.

Specification of Letters Patent.

Patented Oct. 9, 1917.

Application filed November 15, 1912. Serial No. 731,621.

To all whom it may concern:

Be it known that I, MATTHEW H. LOUGHRIFFE, born in county Antrim, Ireland, naturalized a citizen of the United States, and 5 a resident of Bogota, in the county of Bergen and State of New Jersey, have invented certain new and useful Improvements in Railway - Traffic - Controlling Systems and Apparatus, of which the following is a specification, reference being had therein to the accompanying drawings, forming a part thereof.

Among the principal objects which the present invention has in view are: to provide a system as characterized with independent moving members, each having a regular permitted area of travel, and station means normally operable to re-establish the permitted area; to provide a system 10 having movable vehicles, each self-controlled to stop at the end of a predetermined distance period, and a series of devices disposed at intervals and operable to re-initiate the predetermined period of travel prior to the 15 expiration of the preceding period; to provide the vehicles above mentioned with an actuating mechanism for the brakes thereon, said mechanism operating in correspondence with the running gear of the vehicles to activate the brakes on said vehicles at a certain 20 predetermined period in the operation of said mechanism; to provide a re-initiating apparatus for said mechanism, operable from the roadbed to re-set the operative 25 parts of said mechanism to the starting point in the operation thereof when impelled thereto by an obstruction on the roadbed; to provide a simplified and compact construction for the mechanism above mentioned; to provide a series of station devices 30 for normally actuating the re-initiating apparatus during the normal operation of the above-mentioned actuating mechanism; to provide a series of operating blocks, each 35 having a station device of the character mentioned, positioned in advance of the end of its block a distance equal to the travel period in which the said actuating mechanism is operative; to provide means for automatically 40 re-setting said actuating mechanism after the expiration of the operating period

thereof; and to provide automatic means for correcting the operation of said actuating mechanism.

In the drawings:

Figure 1 is a perspective view of a railway vehicle truck having mounted thereon a transmission mechanism and a trip mechanism constructed and arranged in accordance with the present invention;

Fig. 2 is a sectional elevation of an actuating mechanism for a brake-setting mechanism constructed and arranged in accordance with the present invention;

Fig. 3 is a face view of a dial and pointer used in conjunction therewith to show the operation of said actuating mechanism;

Fig. 4 is a detail view showing a portion of the transmission mechanism for rotating said pointer and the shaft connected therewith;

Fig. 5 is a diagrammatic view showing a section of a track-bed divided into blocks and arranged for operation in accordance with the present invention;

Fig. 6 is a similar view, showing a modified form of the arrangement and devices for operating the re-initiating mechanism of said vehicles;

Fig. 7 is a similar view, showing a modification of the arrangement above mentioned, and particularly as applied to, and modified by, a switch turn-out on the track-bed.

The present invention consists primarily of two factors; first, an equipment for the locomotive or other moving member of a railway system, constructed and arranged to normally operate at regular intervals to set its brakes; and second, an automatic operating series of blocks, each having station means for re-setting or re-initiating said equipment, to extend or re-establish the permitted area of travel

The equipment referred to is operated from the axle connecting the wheels 11 and 11^a, which rest on the track rails 3 and 3^a. On said axle is fixed a worm 12, with the thread of which the teeth of a worm wheel 13 are in mesh. The wheel 13 is suitably mounted in bearings formed on the truck frame 10, and the axle of said wheel is con-

5 nected through a chain 14 to a short shaft 15, on which is formed a worm 16. The shaft 15 is suitably mounted in brackets 32 projected from a split plate 33, as best seen in Fig. 4 of the drawings.

6 The worm 16 is meshed with the teeth of a worm wheel 17 which is fixedly mounted on a short shaft 18. The shaft 18 is mounted in bearings formed by a fixed collar 18^a and 10 a loose collar 18^b. The loose collar 18^b is pocketed to hold on one side the outer end of the shaft 18 and on the other side a compression spring 34. The spring 34 is held in 15 a pocket formed in a bracket 39 mounted on the main frame 30 of the actuating mechanism.

7 The split plate 33 is slidably mounted on the frame 30, elongated slots being formed in said plate 33, through which extend the 20 holding screws 33^a, 33^b, 33^c and 33^d. The plate 33 and parts mounted thereon are moved forward to force the female member 19 against the male member 19^a, which members constitute a friction clutch for the transmission of rotary motion to the shaft 20.

8 On the shaft 20, and at the outer end thereof, is mounted a pointer hand 21, designed to travel over a dial 21^a, on which are placed the numbers "0," "1000," "2000," and "3000," 25 these numbers indicating the initial or starting point of travel and the number of feet traveled by the vehicle over the tracks 3 and 3^a. The dial is further provided with a color section 21^b, intended to indicate 30 visually that the vehicle is approaching the point where, if not manually controlled, it will be automatically or self-controlled, or stopped, by setting the brakes thereof. The shaft 20 is retracted to place the pointer 21 over the point marked "0," by a spring 24. The spring 24 operates whenever the clutch 19, 19^a, is released.

9 It is to release the clutch 19, 19^a that I provide cams 36, 36^a, the arms 37, 37^a, of 45 which are connected to the rod 9. As the rod 9 is lifted or depressed to carry the arms 37, 37^a from the normal or horizontal position, the end extensions of the cams 36, 36^a bear against lugs 38, 38^a on the split 50 plate 33, to force the same back, compressing the spring 34 and separating the male and female members 19 and 19^a of the clutch. The rod 9 is normally operated in the manner above indicated when the trip arm 5 is 55 engaged and moved by the plunger 4 on the track-bed of the railway. The arm 5 is the free arm of a bell crank, which is pivoted at 6 on the journal box or other part of the truck connected preferably directly with 60 the wheels of the truck, to avoid the action of the carrying springs thereon. The connected end of the bell crank is pivoted to the connecting rod 8, which is pivoted to a rocking arm 8^a. The rocking arm 8^a is 65 pivoted suitably in bearings mounted on the

truck, and is pivotally connected at the opposite end to the rod 9. The arm 5 is held in the vertical or alert position by the weight 7.

70 From the foregoing, it will be seen that when a vehicle having a truck equipped in the manner described, passes over a track-bed provided with devices having the plunger 4, the trip arm 5 will be deflected by said plunger to either raise or lower the 75 rods 8 and 9 to rotate the cams 36 and 36^a, whether the vehicle be moved forward or backward. As the ends of the cams 36 and 36^a are each equally eccentric, the rotation 80 thereof operates to force backward the lugs 38, 38^a and split plate 33, together with the shaft 18 and clutch member 19. This effects, in releasing, the member 19^a, and the shaft 20 is free to be retracted by the spring 24, 85 until the shaft is arrested by the lug 26 engaging the stop 25, in which position, it will be found that the pointer 21 is opposite the "0" mark on the dial 21^a.

90 Fixedly mounted on the shaft 20 is a cam 22, on the periphery whereof travels a wheel 40^a. The wheel 40^a is suitably mounted in the forked end of the rod 40. The rod 40 is normally depressed by a spring 40^b to hold the wheel 40^a on the cam 22. 95 The free end of the rod 40 is suitably connected with a brake-setting mechanism, with which the vehicle, locomotive, or car is provided, such as, for instance, a compressed-air operated brake system. If operated by compressed air, the rod 40 is preferably 100 connected with some device or mechanism for reducing the pressure in the train pipe. The above-mentioned device is not shown in the drawings.

105 The cam 22 is arranged on the shaft 20 so that when the pointer 21 passes over the section 21^b of the dial 21^a, the peak of the cam 22 lifts the rod 40 to actuate the brake-setting mechanism of the vehicle or train. Thus, it becomes necessary for the continuous travel of the vehicle or train that the 110 clutch members 19 and 19^a be released, and the spring 24 permitted to retract the shaft 20 to its initial position prior to the pointer 21 passing above the section 21^b. For this 115 purpose, the plungers 4 are disposed in advance of what may be termed the terminal of each block, or in other words, the plunger or plungers belonging to each block of the track-bed overlap the preceding block. As hereinafter described, the plungers are 120 held in raised or operative position when the track is clear for the running of the vehicle or train, and lowered or removed from operative position when the track is not clear, or when, for any reason, the operating mechanisms controlling said plungers have become broken or disarranged. It will be remembered that when the plungers are in 125 operative position, the trip arm 5 and rods 130

8 and 9 connected therewith, together with the cams 36, 36^a, are operated to retract the split plate 33 and to thereby release the shaft 20 to permit the spring 24 to retract the pointer 21 and the cam 22 to their initial points of travel, thus re-initiating the permitted area of travel for the vehicle or train.

Before proceeding to the description of the block arrangement and the disposition of the plungers 4, it is thought best to explain the operation of the cam 23, which is fixedly mounted on the shaft 20 and the rod 41 with which it is connected. The lower end of the rod 41 is forked to form bearings for the wheel 41^a. The wheel 41^a tracks on the cam 23, the peak or high point of which is arranged to follow at a suitable interval after the peak or high point of the cam 22. Laterally extended above the rod 41, and in the path thereof, is a small pallet 9^a, by which the rod 9 is lifted by the rod 41. The lifting of the rod 41 reestablishes the active positions of the cams 36, 36^a, to effect the disengagement of the male and female members 19, 19^a of the clutch operatively connecting the shafts 18 and 20.

In this manner, if the engineer or driver of the train or vehicle neglects to reestablish the operating condition of the actuating mechanism for the brake-operating mechanism, the same is automatically performed by the mechanism itself; or, in other words, the engineer or driver is not called upon to reestablish or re-arrange said mechanism. In this manner, provision is made not alone for operating the brakes of the vehicle or train if run onto an obstructed block, but provision is likewise made for the reestablishment of the operating condition of said mechanism.

As shown in the accompanying drawings, it is preferred to operate the plungers 4 electrically, and also to operate them by what is known as the "closed-circuit electric system," or by means of circuits, each of which normally energizes the solenoid or magnet 1 supported on the road-bed by the stand 2, at the side of the tracks 3 and 3^a. The operation of the solenoids 1 in the preferred form of the device normally elevates the plunger 4 into the path of the trip arms 5.

In Figs. 5, 6 and 7 of the drawings is shown a variety of forms of applications of the invention. As a rule, the blocks are each provided with an operating circuit embodying a battery such as indicated in the drawings by the designations *g*, *ga*, *gb*, *gc* and *gd*, the track rails 3 and 3^a, branch wires *T* and *T'*, and some form of electric operating devices normally active to elevate the plungers 4. The batteries mentioned are connected with the rails at the far ends of the various blocks, and the wires *T* and *T'* of the track relay *R* are connected with

the rails at the inner or entrance end of said blocks, while the plungers are each disposed in advance of said entrance end of the block a distance calculated with reference to the traffic conditions, agreeable to the proper application of the brakes to arrest the train prior to entering the block to which the plungers belong, in the event of the plungers failing to operate to extend the permitted area of travel of the vehicle or train. By means of this arrangement, each vehicle or train, after entering a block, operates to shunt the wires *T*, *T'* and operating devices connected therewith, to permit the plunger 4 to drop from the path of the trip arms 5, which thus failing to re-initiate the actuating mechanism for the brake-setting mechanism, permits the same to automatically set the brakes of the vehicle or train.

In Fig. 5 of the drawings, and at the left-hand end thereof, an arrangement is shown whereby the plunger 4 for permitting travel of the vehicle on the block A—B, is manually controlled. In this arrangement, the solenoid 1 is placed in circuit with the battery *P* by means of a switch *M* and wires *x*, *y*. When the switch is closed, as shown, the plunger is elevated. When an operator desires to close the block A—B, he pulls the switch *M*, which thereby de-energizes the solenoid 1, permitting the plunger 4 to drop, with the consequent effect on the actuating mechanism for the brake-setting mechanism of the next succeeding train, of causing the brakes thereof to set if the train passes the station *a* where said plunger 4 is disposed.

The preferred form of arrangement is that shown in Fig. 5 in relation to the block B—C. In this arrangement, it will be seen, the local circuit embodying the wires *x*, *y* and the battery *P* is controlled by a switch member *m*. The switch member constitutes an armature for an electro-magnet *R*. The electro-magnet *R* is incorporated in the circuit embodying the rails 3, 3^a and battery *gb*.

In operation, it will be seen that when the block B—C is clear, the circuit embodying the battery *gb* energizes the magnet *R* to draw the armature switch *m* to the terminal *K*, thus completing the local circuit embodying the battery *P* and solenoid 1. The solenoid being thus energized, the plunger 4 is lifted into the path of the trip arms 5. In this position, the vehicle or train, when passing the station *b*, will be operated upon to re-initiate its permitted area of travel, which is measured to terminate at the break between the blocks B—C and C—D.

If the track-bed is equipped throughout with a system having this arrangement, then a second local circuit embodying the solenoid 1 would be set opposite the station *c*, and again repeated at the station *d*.

If, in the operation of trains, a vehicle passes on the block B—C between the wires

4
 T, T' and the battery $g\delta$, the magnet R is deenergized to release the armature. The armature switch m moves out of engagement with the contact K, thereby breaking the local circuit in which the solenoid 1 is incorporated. The solenoid 1 being thus deenergized, the plunger 4 is permitted to fall, and thus pass out of the path of the trip arms 5. It will now be seen that should a following train or vehicle undertake to enter the block B-C, the actuating mechanism for the brake-setting mechanism thereof would fail to be re-set, and the cam 22 would lift the rod 40 up, to actuate the brake-setting mechanism when the train arrived at the station b , or before the train passed onto the block B-C.

The arrangement of the solenoids, circuits and operating magnets connected with the block C-D and the block beyond D, provides for a system where it is desired to operate over two or more blocks and thus to lengthen the operating intervals between vehicles. Referring to the drawings, it will be noted that opposite the stations c 1 show a solenoid 1, having a local circuit x, y, γ , battery P and armature switch m , as in the arrangement opposite the station b . Also, the branch wires T, T' and relay or magnet R operates the armature switch m when energized to complete said local circuit. This circuit, with a corresponding plunger 4 and solenoid 1, operates to control the admission to the block C-D.

35 It will also be noted from Fig. 5 that a second solenoid 1^e and a corresponding plunger 4^e located near but in a different horizontal plane from plunger 4 above described, are provided at the station c .
 40 Solenoid 1^e is controlled by two block sections C-D and D— through relays R and Rd respectively. The controlling circuit can be traced from contact kc , armature m' of relay R, wire x' , battery P at location D, contact kd , armature m' of relay Rd for section D— and wire y' to other side of solenoid.

When the track-bed is thus equipped, the vehicles operated thereon are each provided 50 with a second actuating mechanism, the transmission of which is geared down, to provide a distance interval of travel for the vehicle twice that provided by the above described mechanism.
 55 It will be noted that when a vehicle such as that indicated by W in Fig. 5 of the drawings, passes onto the block C-D, it deenergizes the magnet R, and by releasing the switches m and m' , opens the local circuits 60 and deenergizes the solenoids 1 and 1^e to permit the plungers 4 and 4^e to move out of the path of the trip arms 5 of succeeding vehicles or trains.

65 If a following vehicle or train passes into the block C-D while the vehicle W is in

said block, its brake-setting mechanism would be operated by reason of the plunger 4 failing to engage the arm 5 thereof. If the vehicle W passes out of the block C-D before the following train reaches the station c , then the plunger 4 will be elevated to engage the arm 5 of the brake-setting actuating mechanism, while the plunger 4^e will remain lowered when the train is passing over blocks C-D and D. As the following vehicle now passes the station c , the first-mentioned brake-setting actuating mechanism is re-initiated, but the second-mentioned actuating mechanism by avoiding the second arm 5 permits the set of the brakes. The engine driver may ascertain by consulting the pointer 21 that the brakes were set by the controls of the block ahead of that next succeeding. It is understood that for the second brake setting actuating mechanism above mentioned a suitable signal may be substituted.

As distinguished from the former state of the art, the present invention provides for operating the controls in systems where in the blocks are unequal in length and independently if desired by the blocks and are regulated by the traffic needs of the railway.

Fig. 6 of the drawings is employed to show a system wherein the blocks are of unequal length, and where they are partially controlled by semaphores or visible signals, which semaphores are operated in conjunction with the plungers 4 by means of the solenoids 1, or equivalent devices. In this figure the normal length of block for which the actuating mechanism is set, is indicated by the distance F. The block A-B is arranged to illustrate the application of the system to blocks longer than the normal length, the assumed excess distance in this case being indicated by G. As in the arrangement disclosed in Fig. 5 of the drawings, the operating stations a and b are slightly in advance of the separations between the blocks indicated by A and B. It is evident that if the plunger 4 at the station a should engage the arm 5 and re-initiate the actuating mechanism, the permitted travel period would expire before the vehicle reached the station b or when it is from it a distance equivalent to G, with the effect that the vehicle or train would be stopped by the setting of its brakes in the manner described. To avoid this, a second plunger 4^a and a second solenoid 1^a are placed in the path of the arms 5 at a distance backward from the station b equal to the travel period of the vehicle above referred to that is, to the normal length of block F. The solenoids 1 and 1^a , with their respective plungers 4 and 4^a , are both in circuit with the battery P, and are controlled by the closing of the armature

- switches m and m' upon the contacts k and k_a . The armature switches m , m' are controlled by the magnet R , which is normally energized by the battery ga belonging to the block A—B. The plunger 4^a has at the bottom a cross piece, which, when said plunger is elevated, engages the contacts k^2 , k^3 to complete a local circuit independently of relay R embodying the solenoid 1^a .
- 5 Part of this circuit is the spring S , which is disposed beside the track 3 and arranged to be depressed by the wheel of a passing vehicle. Normally, the spring contact S engages the contact k^4 forming part of the local circuit in which the solenoid 1^a is incorporated.
- 10 Part of this circuit is the spring S , which is disposed beside the track 3 and arranged to be depressed by the wheel of a passing vehicle. Normally, the spring contact S engages the contact k^4 forming part of the local circuit in which the solenoid 1^a is incorporated.
- 15 When a roadbed is thus equipped, and when the block A—B is clear, a vehicle, in passing the plunger 4 at the station a , has its actuating mechanism re-set or re-initiated thereby. Normally, the local circuit embodying the battery P , solenoid 1^a , contacts k^2 , k^3 , k^4 and spring contact S , is closed, and the plunger 4^a is elevated to complete the circuit through the contacts k^2 , k^3 . When the vehicle passes the junction with the rails 3, 3 a and the wires T , T' , the magnet R at the station a is de-energized, and the armature switches m , m' are dropped from the contacts k and k_a , opening the local circuit embodying the solenoid 1^a , and also opening the branch circuit having the wire x' and the contact k . The immediate result of the de-energizing of the solenoid 1^a is to drop the plunger 4, closing the block A—B to a following vehicle or train. Solenoid 1^a , when energized, remains energized independently of relay R by a holding circuit until switch S is opened by a passing
- 20 train. This holding circuit can be traced from battery P , wire y , solenoid 1^a switch S , contact k^4 , wire to contacts k^2 and k^3 and wire to other side of battery. The plunger 4^a is thereby maintained in elevated position
- 25 until the vehicle or train on the block A—B passes said plunger and operates the spring contact S to separate it from the contact k^4 . This break in the local circuit de-energizes the solenoid 1^a , and drops the plunger 4^a from the contacts k^2 , k^3 , but prior to this drop of the plunger 4^a , the same has engaged the arm 5 and re-initiated the actuating mechanism on the vehicle, renewing thereby the permitted area of travel for the vehicle,
- 30 or re-establishing the actuating mechanism to operate at or approximate to the end B of the block A—B. It will be understood that the auxiliary plunger 4^a is placed with reference to the end of the block backward therefrom a distance corresponding to the area of travel for which the actuating mechanism above described, is designed.
- 35 It will be understood that while I have described the use of one auxiliary plunger and solenoid having a self-closed circuit,
- more than one may be used where needed, to provide for unusual lengths of blocks, but in every case, the last auxiliary plunger and solenoid will be disposed at a distance from the end of the block corresponding with the travel area provided in the actuating mechanism.
- 40 From the above, it will be seen that the plungers 4 and 4^a are dropped successively, and that both remain in this position until the vehicle passes out of the block A—B, when the magnet R at the station a is re-energized, to close the switches m and m' and the local circuits embodying the solenoids 1 and 1^a , the latter using the wire x' and the closed spring contact S . With the lift of the plunger 4^a , the independent local circuit for the solenoid 1^a is closed by the plunger engaging the contacts k^2 , k^3 , and the instruments at the station a are simultaneously re-established in position to re-initiate the traveling area of the vehicle passing onto and from the block A—B.
- 45 The above description has undertaken to show the adaptation of the system to a block longer than the travel area permitted by the actuating mechanism carried by the vehicle. The blocks B—C and C—D are designed to show the adaptation of the system to blocks having a lesser area of travel than that permitted by the actuating mechanism. The solenoid 1 and plunger 4 at the station b are arranged and operated as above described. The circuit embodying this solenoid, however, controls through blocks B—C and C—D by contact kb of relay for section B—C, wire y and contact kc of relay for section C—D, battery P and return wire x to solenoid. Therefore, the circuit operating to re-energize the solenoid 1 at the station b is not closed until after the vehicle passes out of the block C—D.
- 50 The permitted area thus established at b expires within the block section C—D which is a lesser distance than that over which the plunger at b is controlled. Within this distance another plunger is located at c controlling through the blocks C—D and D—E by the contact kc of track relay R for section C—D, wire y , contact kd of relay R for section D—E, battery P and return wire x . Thus the permitted area established at c expires within the block section D—E, which is a lesser distance than that through which the plunger at c controls. Within this distance another setting device is located at d in normal relation to block D—E which is of normal length, thus establishing normal conditions for succeeding blocks of uniform length. The semaphore signals L may be used to mark each block.
- 55 It will thus be seen that the plungers 4 control through succeeding short blocks until the normal length of block is equaled or exceeded, this condition being repeated at

60 65 70 75 80 85 90 95 100 105 110 115 120 125 130

each short block. When a block or normal or greater than normal length is reached, the last plunger is located the normal distance from the end of this block so that 5 under no conditions can a plunger give permission to proceed over a greater length of track than is clear.

The apparatus shown at the station *e* at the beginning of the block *E*— is constructed and arranged as shown and described as 10 at the station *b* in Fig. 5.

In Fig. 6 of the drawings, I have shown at each of the operating stations the plungers 4 as mechanically connected by means 15 of an arm *N* with a semaphore *L*. By this means, it will be understood that if it is desired to incorporate the visual signal, such as the semaphore *L*, with the control system herein disclosed, this may be accomplished 20 substantially in the manner indicated.

In Fig. 7 an adaptation of the system to two distinct purposes is shown, namely; an arrangement for making the brake setting mechanism effective at any desired point on 25 the track. Control of the train within the block may be desirable where the speed is high and where the succeeding block is short, or where there is not sufficient distance to stop the train before encountering an obstruction. A train running at normal speed 30 and failing to have its brakes setting mechanism reinitiated at station *b* for instance, would not have sufficient distance in which to stop before reaching station *c*; if however, 35 the train is controlled to a safe speed before reaching station *b*, this condition will not occur. This is secured by controlling the speed of the train within the block *A*—*B* so that it will not be exceeding a safe speed 40 when passing the point *b*.

For this purpose a plunger is located at *A'*, the solenoid of which is controlled in a multiple circuit with the solenoid of the plunger at *b* by the wires *ya* and *xa*. The 45 plunger located at *A'* performs a function similar to plunger 4^a in Fig. 5, that is, it operates a second, or caution brake actuating mechanism applied to control the speed of the train and, if desired, for operating a 50 suitable signal. In practice, when block *B*—*C* is obstructed, a following train may proceed at high speed from *A* to *A'*. At the latter point a caution signal becomes effective, requiring a reduction in speed 55 before reaching station *b* so that the train may be able to stop within the short block *B*—*C*. When block *B*—*C* is clear, the plunger at location *A'* reinitiates the caution 60 brake setting mechanism, thus allowing high speed to be maintained.

In Fig. 7 of the drawings, and at the station *d* thereof indicated thereon, the application of the system to obtain control at a switch is shown. The plunger 4 and sole- 65 noid 1 for operating the same at the station

d are similar in construction and operation to the system shown and described as at the station *b* in Fig. 5. The local circuit for energizing this solenoid however, incorporates a spring contact member *S*, which is 70 mechanically connected with the movable member 3^b of a switch, to be moved in unison therewith. When the switch is closed, or the main track is clear, the contact *S*, through the rod *O*, is moved to engage the 75 contact *K*⁴, which completes the circuit energizing the solenoid 1, and lifts the plunger 4 thereof into the path of the arms 5, to re-initiate the actuating mechanism of the passing vehicle or train. When, however, 80 the member 3^b is moved to close the switch or turn-out, the contact *S* is removed from the contact *K*⁴, and the circuit is broken, deenergizing the solenoid, and dropping the plunger 4, to permit the actuating mechanism 85 to set the brakes on the passing vehicle. The vehicle, on passing onto the block beyond *D* on the main line, or onto the turn-out, shunts the magnet *R* at the station *d*, and thereby drops the switch member, to 90 open the circuit embodying the solenoid 1, permitting the plunger 4 to drop to inactive position.

It will be noted that in this figure the station *d* is located at, or near, the point of 95 obstruction which it is desired to protect and in order to secure this effect and maintain the normal operation of the system, the short block *B*—*C* is introduced between this block and the blocks to the rear of normal length as *A*—*B*. The plunger at *b* controls 100 through sections *B*—*C* and *C*—*D* similar to that at *c*, Fig. 6. It will thus be observed that by an arrangement of this kind, it is possible to make the brake setting mechanism 105 operate to stop the train at any point on the track desired while maintaining complete block protection.

In the operation of railway traffic, and under the varying weather conditions, provision should be made for the slipping of the wheels on the track incident to faulty application of brakes, or unforeseen conditions of the track. Where the actuating mechanism is driven by the wheels of a 110 vehicle, this slippage may result from variance between the operating period of the brake-setting actuating mechanism and the travel area provided on the road-bed. To accommodate this, I provide for the placement of the plungers 4 in advance of the termination of each of said blocks, or of the operating point under normal conditions, for the actuating mechanism. In sections of track where the liability to such inaccuracy 115 of operation is prominent, this is provided for by an increased lead of the operating position of the plunger 4 over the end of the block. This also is provided for by re-setting the cam 22 of the actuating mecha- 120 125 130

nism of each vehicle with reference to the operating station thereof.

- While I have herein described the construction and operation of the pointer 21 and mechanism connected therewith as actuating the brake-setting mechanism at a predetermined time, it will be understood that the same may be utilized to show any failure on the part of said mechanism to operate.
- 10 If the driver of the vehicle at any time notes that the pointer 21 is not moving, this fact will immediately advise him that the mechanism is not operating, and is not to be relied upon.
- 15 Where, as above described, two or more actuating mechanisms are employed, having dials such as 21^a and pointers 21 moving thereover, the transmission mechanism connecting the running gear of the vehicle and the shaft 20 of each of said actuating mechanisms may be so varied that overlapping systems may be employed to operate for setting the brakes independently, or in the nature of cab signals.
- 25 Having thus described my invention and shown some methods of how it may be applied, I claim:

1. In a railway traffic controlling system, the combination on a locomotive, of a moving indicator driven by reduction gearing from the running wheels, a cam revolving with said indicator, a member for controlling said locomotive, said member operated by said cam, said cam being adjustable to operate said member at any position relative to the position of said indicator.

2. In a railway traffic controlling system, the combination on a locomotive, of a friction clutch, a plurality of shafts, one of said shafts driven by reduction gearing from the running wheels, a controlling mechanism connected with the other shaft, said shafts connected by said friction clutch, means for disconnecting said friction clutch and means for setting said mechanism to the starting position when so disconnected.

3. In a railway traffic controlling system and apparatus, in which the track is divided into blocks or sections, the combination of an indicator consisting of a dial having a revolving pointer, said pointer being driven by reduction gear from the locomotive wheels, a trip arm placed alongside of the tracks near the beginning of each of said blocks, and means operated by the trip arm for setting said pointer to the starting position before entering a block or section, the angular movement of the pointer on the dial indicating the distance the locomotive has traveled in said block or section.

4. In a railway traffic controlling system and apparatus the combination on a locomotive of an indicator consisting of a dial having a revolving pointer driven by a reduction gear from said locomotive wheels, a

trip arm placed alongside of the track, means operated by said trip arm for setting said pointer to the starting position.

5. In a railway traffic controlling system and apparatus, the combination, a track 70 divided into a plurality of block sections, a locomotive having a controlling mechanism, said mechanism embodying a plurality of moving members and connecting means, one of said members driven by the movement of said locomotive on said track, another shaft 75 driven by said connecting means from said first mentioned member, devices on the track disposed with relation to said block sections and means for releasing said connecting 80 means by said track devices.

6. In a railway traffic controlling system and apparatus, a track divided into a plurality of block sections, a locomotive having a controlling mechanism embodying a plurality of moving shafts and connecting means, one shaft driven by the movement of said locomotive on said track, another shaft 85 driven by said connecting means from said first mentioned shaft, devices on the track 90 responding to clear track conditions in said block sections and means for releasing said connecting means by said track devices when said block sections are clear.

7. In a railway traffic controlling system, the combination, a track, a locomotive having a controlling mechanism, said mechanism embodying a plurality of shafts and connecting means, one of said shafts driven by the movement of said locomotive on said 100 track, another shaft driven by said connecting means from said first mentioned shaft and having a cam fixed thereon, means for releasing said connecting means by the movement of said cam.

8. A vehicle having an automatic brake-actuating mechanism operable at fixed intervals; and a track-bed having blocks; each provided with stations to normally suspend the operation of said brake-actuating 110 mechanism, one of said stations being removed from the terminal of each block a distance corresponding with said intervals, and the other of said stations being removed from said terminals a distance greater than 115 said intervals.

9. A vehicle having an automatic brake-actuating mechanism operable at fixed intervals; a track-bed having blocks, each provided with stations to normally suspend the 120 operation of said brake-actuating mechanism, one of said stations being removed from the terminal of each block a distance corresponding with said intervals, and the other of said stations being removed from said terminals a distance greater than said intervals; and means operable by a vehicle in passing, for suspending the operation of said stations successively.

10. A vehicle having an automatic brake- 130

- actuating mechanism operable at fixed intervals; a track-bed having a plurality of blocks of various lengths; and a plurality of operating stations on said track-bed, for suspending the operation of said brake-actuating mechanism, each of said stations being controlled by one of said blocks and disposed in advance of the terminal thereof a distance corresponding with said intervals.
11. A vehicle having an automatic brake-actuating mechanism operable at fixed intervals; a track-bed having a plurality of blocks of various lengths; a plurality of operating stations on said track-bed, for suspending the operation of said brake-actuating mechanism, each of said stations being controlled by one of said blocks and disposed in advance of the terminal thereof a distance corresponding with said intervals; and means automatically operable for re-initiating the operation of said brake-actuating mechanism.
12. A vehicle having an automatic brake-actuating mechanism operable at fixed intervals; a track-bed having a plurality of blocks of various lengths; a plurality of operating stations on said track-bed, for suspending the operation of said brake-actuating mechanism, each of said stations being controlled by one of said blocks and disposed in advance of the terminal thereof a distance corresponding with said intervals; and means embodied in said brake-actuating mechanism for automatically re-initiating the operation of said mechanism after the same has been suspended.
13. A vehicle having a brake-actuating mechanism automatically operable at fixed intervals; a driving mechanism for said brake-actuating mechanism, embodying carrying wheels of said vehicle; means for retracting said brake-actuating mechanism when released from said driving mechanism to the starting point of said brake-actuating mechanism; a releasing mechanism for said brake-actuating mechanism, embodying a movable member operable from the track-bed; a track-bed having a series of blocks; a plurality of adjustable interference members normally disposed in the path of said movable member, each of said interference members being disposed in advance of the terminal of one of said blocks; and operating means for said interference members, disposed in each of said blocks, for normally holding said interference members in the path of the movable member of said releasing mechanism.
14. A vehicle having a brake-actuating mechanism automatically operable at fixed intervals; a driving mechanism for said brake-actuating mechanism, embodying carrying wheels of said vehicle; means for retracting said brake-actuating mechanism when released from said driving mechanism to the starting point of said brake-actuating mechanism; a releasing mechanism for said brake-actuating mechanism, embodying a movable member operable from the track-bed; a track-bed having a series of blocks; a plurality of adjustable interference members normally disposed in the path of said movable member, each of said interference members being disposed in advance of the terminal of one of said blocks; and operating means for said interference members, disposed in each of said blocks, for normally holding said interference members in the path of the movable member of said releasing mechanism.
15. A system as characterized, having a track-bed; a plurality of vehicles moving thereover; an indicator carried by each vehicle and driven by the carrying wheels thereof; an associated mechanism for controlling said vehicles having a moving cam operatively connected with said indicator; and means operatively connected with said cam for operating said associated mechanism.
16. A system as characterized, having a track-bed; a plurality of vehicles moving thereover; an indicator carried by each vehicle and driven by the carrying wheels thereof; an associated mechanism for controlling said vehicles having a moving cam operatively connected with said indicator; means operatively connected with said cam for operating said associated mechanism; and means for altering the operative movement of said cam.
17. A system as characterized having a track-bed; a plurality of vehicles moving thereover; a controlling mechanism carried by each vehicle embodying a plurality of moving members and a moving indicator, one of said members driven by the running wheels of said vehicle; means permanently disposed at predetermined points on the track-bed for automatically re-setting said mechanism, said indicator disclosing the operative condition of said mechanism.
18. A railway traffic controlling system comprising automatic traffic controlling means carried on a railway vehicle and having a retarding and a non-retarding condition, the said means being constructed and arranged to assume retarding condition within a limited interval and means located in the trackway and constructed and arranged to restore the traffic controlling means away from retarding condition; also, means embodied in said traffic controlling means for setting it away from retarding condition when said track means fail.
19. In combination, a railway track, a ve-

- hicle adapted to travel thereon, a controlling mechanism on said vehicle arranged to operate at fixed intervals, said mechanism embodying means for resetting itself at fixed intervals of travel of said vehicle.
20. In combination, a railway track, a vehicle adapted to travel thereon, a controlling mechanism on said vehicle arranged to operate at fixed intervals of travel, said mechanism embodying means for resetting itself at intervals of travel greater than said fixed intervals.
21. In combination, a railway track, a vehicle adapted to travel thereon, a controlling mechanism on said vehicle arranged to operate at fixed intervals of travel, devices on the trackway to reset said mechanism, said mechanism also embodying means for resetting itself when said track means fail to reset it.
22. In combination, a railway track, a vehicle adapted to travel thereon, a controlling mechanism on said vehicle arranged to operate at fixed intervals of travel, devices on the trackway adapted to reset said mechanism, said mechanism embodying means for resetting itself after said operation.
23. In a railway traffic controlling system, the combination, a track, a locomotive having a controlling mechanism, said mechanism embodying a plurality of moving members, one of said members and connecting means, driven by the movement of said locomotive on said track, another member driven by said connecting means from said first mentioned member and having a device for releasing said connecting means by its movement.
24. In combination, a railway track, a vehicle adapted to travel thereon, a controlling mechanism on said vehicle arranged to operate at fixed intervals of travel of said vehicle, a block system dividing said track into sections of various lengths, devices located on said track at intervals, each controlled by said block system over a greater portion of track than said fixed interval, said devices being located in spaced relation to each other a distance not exceeding said fixed interval, said devices arranged to set said controlling mechanism away from controlling position.
25. In combination, a railway track, a vehicle adapted to travel thereon, a controlling mechanism on said vehicle arranged to operate at fixed intervals of travel of said vehicle, a block system dividing said track into sections of various lengths less than said fixed intervals, devices located on said track at intervals controlled by a plurality of said block sections, said devices arranged to set said controlling mechanism away from controlling position.
26. In combination, a railway track, a vehicle adapted to travel thereon, a controlling mechanism on said vehicle arranged to operate at fixed intervals of travel of said vehicle, a block system dividing said track into sections of various lengths exceeding said fixed interval, a plurality of devices located in each block and arranged to set said controlling mechanism away from controlling position, said devices spaced not exceeding said fixed interval apart, and the last device spaced said fixed interval from the end of said blocks.
27. In combination, a railway track, a vehicle adapted to travel thereon, a plurality of controlling mechanisms on said vehicle each arranged to operate at fixed intervals of travel of said vehicle, a block system dividing said track into sections, a plurality of devices located on said track and controlled by said block system, said devices arranged to set said mechanism away from controlling position, the control of each device being arranged to correspond with the said fixed interval of the particular mechanism which it operates.
28. In combination, a railway track, a vehicle adapted to travel thereon, a controlling mechanism on said vehicle driven by the running gear and arranged to operate at fixed intervals of travel of said vehicle, a block system dividing said track into blocks, devices on the track controlled by said block system for setting said mechanism away from controlling position, said devices located a certain distance within the preceding fixed interval to provide for irregularities in said drive.
- In witness whereof, I have hereunto subscribed my name in the presence of two witnesses.
- MATTHEW H. LOUGHridge.
